CLAIM

The ornamental design for a code attachment housing for a telephone stand, substantially as shown.

DESCRIPTION

FIG. 1 is a top and side perspective view of a code attachment housing for a telephone stand showing my new design;

FIG. 2 is a front elevational view thereof;

FIG. 3 is a rear elevational view thereof;

FIG. 4 is one side elevational view thereof;

FIG. 5 is the other side elevational view thereof;

FIG. 6 is a top plan view thereof;

FIG. 7 is a bottom view thereof; and

FIG. 8 is a top and side perspective view thereof in which a telephone is shown in broken lines for illustrative purposes to indicate operative associational relationship.

FIG. 8
